PACKAGE

Horace F. Phelps, Montgomery, Ala.

Application March 21, 1939, Serial No. 263,283

1 Claim. (Cl. 229—51)

My invention relates to improvements in packages and has as one of the principal objects thereof the provision of a package enclosed within a wrapper of transparent material, for instance cellulose or the like, and which wrapper is fashioned with improved means for facilitating the opening of the wrapper whereby an end of the package may be readily opened in a neat manner to permit access to the contents thereof.

Another object of my invention is to provide a device of the character described which is simple in construction, efficient in operation and economical in manufacture.

Other objects and advantages will be apparent from the following description, appended claim 15 and annexed drawing.

Referring to the drawing wherein like reference characters designate like parts throughout the several views:

Figure 1 is a perspective view of a package 20 having a wrapper constructed in accordance with my invention.

Figure 2 is a perspective view of the same, illustrating the wrapper in partly opened position.

Figure 3 is a detail perspective view of the 25 upper section of the package illustrating the initial operation in the opening of the wrapper.

Figure 4 is a perspective view illustrating the construction of the wrapper on the bottom of the package.

Figure 5 is a top plan view of the blank of material from which the wrapper is formed.

Figure 6 is a detail sectional view taken on the line 6—6 of Figure 5.

In practicing my invention, I provide a package 5 of ordinary construction and which is adapted to contain cigarettes or the like, said package being fashioned with an openable or top wall 6 of a typical overlapping end construction. The package is encased in a wrapper 7 of transparent material, for instance cellulose or the like, and provided with a severable or top wall 8 overlying the wall 6 of said package. The wrapper is integrally fashioned with end walls 9, each comprising overlapping end sections 10 glued or otherwise secured together and which are integrally fashioned with said wall 8.

At the jointures of the end sections 10 with the ends of the wall 8, the walls 9 are provided with folded tucks 11 for effecting a neat fit of the wrapper about the package. The tucks define an inner depending flap 12, the latter folded and integrally connected to the wall 8 and over which are disposed the upper ends of the overlapping sections 10.

One of the flaps 12 is fashioned with a substantially lingulate slot 13 defining a tongue or tab 14, the latter being integrally connected to the wall 8 and disposed over the upper ends of the respective overlapping sections 10 when said wrapper is in closed condition.

Interposed between the walls 6 and 8 is a severing strip 15, the latter preferably constructed of pliable and colored material, for instance cellulose or the like. The strip is secured to the under face of the wall 8 by cement or the like and is of a width less than the width of said severable wall 8.

The side edges of the strip 15 define lines of severage on the wall 8. One end of the strip terminates inwardly an appreciable distance from the end of the wall 8 oppositely disposed from the end on which the tab 14 is disposed. The opposite end of the strip 15 is formed with a normally folded section constituting a tongue or tab 16 and which is secured to the under face of the tab 14 and between the latter and the upper ends of the sections 10 as clearly illustrated in Figures 1 and 4 of the drawing. The tabs are normally maintained folded against the outer faces of the upper ends of the sections 10 by glue or the like and are adapted to be released therefrom by the operator's fingernail or a suitable instrument.

The lower ends of the walls of the wrapper are 30 folded over the bottom of the package and secured in overlapping relation by means of cement or the like and as clearly illustrated in Figure 4. The fold line for forming the heretofore described walls, end sections, flaps and tucks are indicated by the dash and dot lines in Figure 5 of the drawing.

In use, the wrapper is opened by loosening the ends of the tabs as illustrated in Figure 3 and by pulling the same with the fingers sharply across 40 the top of the wrapper whereby the adhering portion of the wall 8 is severed or torn along the lines of severance defined by the edges of the strip 15. The openable wall 6 of the package is thus exposed for manipulation to permit access to the contents of said package.

From the foregoing it will be apparent that I have provided a simple and efficient means whereby a wrapper of a cigarette package or the like may be conveniently and quickly opened.

It is obvious that the invention is not confined to the herein described use therefor as it may be utilized for any purpose to which it adaptable. It is therefore to be understood that the invention is not limited to the specific construction as illustrated and described, as the same is only illus-

trative of the principles of operation, which are capable of extended application in advance forms, and that the invention comprehends all construction within the scope of the appended claim.

What I claim is:

A package having a wrapper which is cut to form an approximately U-shaped tab defining slit, the same wrapper extending continuously about the package by folding the intermediate portion over the top wall and about the front and rear walls and covering the end walls by overlapping end flaps and covering the bottom wall by overlapping folding of the end flaps, the tab de-

fining portion forming an extension of one end of the top wall covering section, the overlapping flaps of the end wall covering sections having folded-in tucks adjacent the ends of the top section, so that the notch from which the tab is struck will be contracted, a severing strip secured to the underside of the top wall wrapper section and the tab to define a severable portion of the said end wall section, and adhesive for detachably connecting the tab portion of the wrapper over the adjacent portion of the end wall covering flaps.

HORACE F. PHELPS.
